UNITED STATES PATENT OFFICE.

CHARLES A. POTTER, OF LAKEPORT, NEW HAMPSHIRE, ASSIGNOR TO UNITED SHOE MACHINERY COMPANY, OF PATERSON, NEW JERSEY, A CORPORATION OF NEW JERSEY.

HEEL-ATTACHING MACHINE.

1,133,575.

Specification of Letters Patent. Patented Mar. 30, 1915.

Application filed February 12, 1908. Serial No. 415,543.

To all whom it may concern:

Be it known that I, CHARLES A. POTTER, a citizen of the United States, residing at Lakeport, in the county of Belknap and State of New Hampshire, have invented certain Improvements in Heel-Attaching Machines, of which the following description, in connection with the accompanying drawings, is a specification, like reference characters on the drawings indicating like parts in the several figures.

This invention relates to heel attaching machines.

In heel attaching machines such as are now commonly used in the manufacture of boots and shoes the attaching nails are brought by a movable nail carrier into position to be driven. The nail carrier is actuated by hand and is supplied with nails at a point removed from the nail driving mechanism.

The primary object of the present invention is to provide a heel attaching machine with means for automatically supplying nails to a nail driving mechanism.

A further object of the invention is to provide a heel attaching machine with nail supplying means which shall not require to be separately actuated by the operator.

In carrying out the invention, I prefer to employ means for bringing nails into position to be driven arranged to be automatically actuated independently of the mechanism for driving said nails. The provision of actuating means independent of the driving mechanism for bringing nails into position to be driven permits the operation of the nail supplying mechanism to be more conveniently timed than is possible where a nail supplying mechanism and nail driving mechanism are operated interdependently.

In order to dispense with the necessity of separately actuating the nail supplying mechanism, a further feature of the invention consists in arranging this mechanism for actuation by a part of the machine which is manually controlled by the operator. According to this part of the invention, the nail supplying mechanism is controlled by the movement by the operator of the shoe support relatively to the nail driving mechanism.

The machine to which the present invention is shown applied includes a nail block provided with nail receiving passages and

with drivers arranged to be automatically reciprocated in said passage to drive the nails into the heel. A shoe support is arranged for movement by the operator into and out of the range of the nail driving mechanism in order to facilitate the application and removal of the shoe.

An important feature of the present invention consists in the provision of means for supplying nails to the nail driving mechanism arranged to be brought into action by the movement of the shoe support, and preferably by its movement out of the range of said nail driving mechanism. With this arrangement the necessity of giving the nail supplying mechanism separate attention is avoided, the supply of nails to said mechanism being effected by an operation incident to removing a heeled shoe from the machine. The construction is preferably such that the nail supplying means is not brought into action until near the end of the outward movement of the shoe support. This is of advantage in that it permits such slight movement of the shoe support as may be required in properly adjusting upon the support the shoe to be heeled, without actuating the nail supplying device.

In the particular embodiment of the invention herein shown and described, a nail carrier is arranged for movement from a nail receiving position into a nail delivering position over the nail block. Means are provided for automatically reciprocating the nail carrier between said positions, said means being brought into action by the movement of the shoe support into inoperative position. Said means is arranged for operation independently of the mechanism for driving the attaching nails, so that it may operate prior to the actuation of said mechanism. In order to insure that the nails shall have time to fall from the nail carrier into the nail block before the former is returned to nail receiving position, the means for reciprocating the nail carrier is constructed to maintain the nail carrier with its nail holes in registry with the nail passages in the nail block for a short interval of time.

Other features of the invention will be hereinafter described and defined in the claims.

In the drawings,—Figure 1 is a view in perspective of a portion of a heel attaching

machine embodying the present invention; Fig. 2 is a view in side elevation with parts in vertical section of the nail carrier actuating mechanism shown in Fig. 1.

5 The present embodiment of the invention is shown applied to a machine having the construction of that shown in United States Letters Patent, No. 884,513, granted to Benjamin F. Mayo April 14, 1908. It will be understood, however, that the invention may 10 be applied to machines of different construction from that shown in said patent.

Referring to the drawings, the machine illustrated comprises a shoe support or jack 2 pivotally sustained at 3 by an adjustable supporting device. A spindle 4 is arranged for movement in a vertical guideway upon the frame of the machine and is reciprocated by automatic actuating means under the control of the operator. A head 6, carrying drivers 8, is secured to the upper end of the spindle 4. The head 6 carries guides 10 mounted on opposite sides thereof and sustained in the lower ends of said guides are 20 springs 12, said springs receiving through them reduced portions of rods 14 arranged to slide in bearings on the head 6, the lower portions of the rods being extended through the guides 10. Said springs 12 have engagement at their upper ends with shoulders upon the rods 14. Secured to the upper ends of the rods 14 is a nail block head carrying a nail block 16 provided with driver passages to receive the drivers 8.

35 As will appear from the patent above referred to, in the operation of the machine containing the parts above specifically referred to, as the spindle 4 is lifted the driver head 6 and nail block 16 rise in unison until the upper side of the heel is pressed into engagement with the heel seat of the shoe sustained by the shoe support 2. After the pressure of the nail block on the heel has reached a predetermined amount, measured 40 by the springs 12, the nail block is arrested, the driver head continues to rise, the upward movement of the drivers independently of the nail block causing the drivers to force the nails from the block into the heel.

50 Rigidly secured to the fixed frame of the machine at the rear of the shoe support is a rod 18. At the upper end of the rod 18 are secured adjustable devices for sustaining a bracket 20 which carries a band clamp 55 22 for receiving and holding in proper positions the heel part of the shoe. A nail carrier arm 24 provided with a nail carrier 25 is pivotally mounted upon the rod 18, said nail carrier being arranged to swing over 60 the nail block and deliver nails thereto. A combined heel holder and top lift holder 26 is pivotally mounted upon the upper surface of the nail block head and is actuated in the manner described in the patent above referred to. Said holder is provided upon its

under side with a roller 28 which is engaged by a member 30 upon the nail carrier arm to swing said holder into the position shown in Fig. 1 in which the heel holder registers with the nail block. The holder is retained 70 in this position by a latch 32, pivotally mounted upon the nail block head, cooperating with a pin 34 upon the holder. A spring not shown is provided to move the holder to bring the top lift holder into alignment with the nail block, the latch 32 being automatically released to permit this movement in the downward movement of the head after the heel attaching nails have been driven; all as is described more in detail in 80 the patent above referred to.

At the rear of the rod 18 which sustains the nail carrier is arranged a stud 36 secured to the fixed frame of the machine. Upon the lower end of the stud 36 is rotatably 85 mounted a driven member 38. Mounted for rotary movement upon the stud 36 above the driven member 38 is a driving member 40 which has upon its upper side a bevel gear 42. Said bevel gear 42 is engaged by a similar gear 44 secured to a horizontal shaft 46 which is continuously rotated in a suitable bearing by a pulley 48, driven from any convenient source. 90

The driven member 38 is provided with a vertical socket near its periphery in which is arranged a plunger 50 provided with a conical head and pressed yielding upwardly by a spring 52. The driving member 40 is provided with a plurality of conical recesses 54 arranged to be entered by the conical head of the plunger 50. The plunger 50 is provided with a pin 56 extending laterally therefrom. Pivotally mounted at 58 upon a projection carried by the rod 18 is a lever 60, the outer end of which is wedge-shaped and provided with a semicircular recess 62 at the rear of the wedge-shaped portion. As will appear from Fig. 2 the lever 60 is arranged to lie between the pin 56 and a flange formed upon the upper end of the driven member 38. A spring 63 is provided to press the lever 60 against the driven member 38. In this position of the lever 60 the plunger 50 is held in inoperative position 105 out of engagement with the driving member 40. When the lever 60 is moved outwardly away from the driven member 38 the plunger 50 enters one of the holes 54 in the driving member and thus causes the 110 movement of the driving member to be imparted to the driven member. 115

It will be understood that there is no novelty in the clutch mechanism *per se* above specifically described, and that other clutch 120 mechanisms could be substituted for that shown without departing from the present invention.

The driven member 38 is provided at its lower side with a wrist pin 64 to which is 125

connected a rod 66. The rod 66 is provided at its forward end with a tubular portion entered by a pin 68. Outward movement of the pin 68 in the rod 66 is limited by a stop 70 which works in a slot formed in the tubular portion of said rod 66. A spring 72 holds the pin 68 in its outermost position. The pin 68 is pivotally connected to a projection 74 upon the nail carrier arm. It will be seen that in a revolution of the driven member 38 the nail carrier will be swung over the nail block and thereafter returned to its original position.

To effect the actuation of the clutch controlling lever 60, there is provided a tripping lever 76 pivotally mounted at 78 upon the clamp bracket sustaining device supported by the rod 18. The outer end of the lever 76 carries a dog 80 pivoted at 82 and held yieldingly against the side of the lever by a spring 84. The dog 80 is arranged to engage the inner end of the lever 60 in the rearward movement of said dog and move said lever 60 out of engagement with the pin 56. As the lever 60 moves away from the pin 56, the dog 80 passes by its inner end and the lever 60 is thus allowed to be returned by the spring 63 into engagement with the side of the driven member 38. In this position it is engaged by the pin 56 at the end of a revolution of the driven member and by its engagement with the said pin depresses the plunger 50 out of operative relation to the driving member 40. The driven member 38 is positively arrested at the end of the revolution by the recess 62 formed in the lever 60, said recess being entered by the pin 56. It will be understood that in the forward movement of the outer end of the lever 76 the dog 80 yields, and thus allows this end of the lever to pass by the inner end of the lever 60. The inner end of the tripping lever 76 is connected to the shoe support 2 by means of a bar 86 which is provided with a notch adjacent to its forward end adapted to pass over a pin 88 carried by the shoe support. I have shown a manually actuated lever 90 for raising the bar 86 out of engagement with the pin 88 in case it is desired to swing the shoe support forwardly without actuating the nail carrier. The lever 90 is normally held in inoperative position by a spring 92.

In the use of the machine above described, assuming that the operations incident to heelng a shoe have been completed, the shoe support 2 is drawn forward by the operator to remove the heeled shoe. Near the end of the forward movement of the shoe support the clutch controlling lever 60 is actuated by the tripping lever 76 to cause a single revolution to be imparted to the driven member 38. The nail carrier 25 is thereby moved into position over the nail block and afterward returned to nail re-

ceiving position. It will be understood that the movement of the nail carrier into nail delivering position is limited by a stop arranged upon the nail block head, as is disclosed in the patent above referred to. This movement of the nail carrier is arrested by said stop before the wrist pin 64 passes the dead center, so that during the middle portion of the revolution of the driven member 38 the nail carrier is stationary. It will be understood that at this point there occurs relative movement between the rod 66 and the pin 68, the spring 72 being compressed. This interval of time during which the nail carrier is stationary may be made of sufficient extent to insure that the nails will descend into the nail block. In the latter portion of the revolution of the driven member 38 the nail carrier is returned to its nail receiving position. It will be understood that in this position it is automatically supplied with nails from a suitable nail assorting apparatus. It will also be seen that, since the heel and top lift holder is actuated in the movement of the nail carrier into nail delivering position, the movement of said holder into operative position is automatically effected and is controlled by the movement of the shoe support.

The reciprocation of the nail carrier and the actuation of the heel and top lift holder occur while the shoe support is in its forward position and prior to the actuation of the nail driving mechanism. It is desirable that the driving lever 76 and clutch controlling lever 60 be so arranged that the clutch mechanism is actuated near the end of the forward movement of the shoe support. After moving a shoe upon the shoe support rearwardly between the members of the band clamp 22, it is frequently necessary to move the shoe support more or less in order to shift the shoe into proper position. By arranging the clutch actuating mechanism so that the clutch is actuated near the forward limit of movement of the shoe support, any liability of the clutch being actuated in adjusting the shoe in the machine is avoided.

The feature of supplying nails to the nail block in the forward movement of the shoe support is of particular advantage in connection with the machine described in the Letters Patent above referred to. It will be understood that in that machine it is necessary to supply the nails to the nail block before inserting a heel and a top lift in their respective holders. In the use of mechanism embodying the present invention, not only is the necessity of performing a separate operation avoided, that of supplying nails to the nail block, but inasmuch as the nails are supplied to the nail block at the close of the cycle of operations of the machine there is less liability of the nail

supplying operation interfering with the performance of other operations incident to preparing the machine for heeling a shoe.

Having described my invention, what I claim as new and desire to secure by Letters Patent of the United States is:—

1. A heel attaching machine, having in combination, a shoe support, power actuated mechanism for attaching a heel to a shoe sustained upon said support, power-actuated means for bringing nails into position to be driven, and means under the control of the operator for effecting the actuation of said means whenever desired, independently of the actuation of said attaching mechanism.

2. A heel attaching machine, having in combination, mechanism for driving nails into a heel, a shoe support arranged for movement into and out of the range of said mechanism, a movable nail carrier for bringing nails into position to be driven, and power actuated means for reciprocating said carrier controlled by the movement of said shoe support.

3. A heel attaching machine, having in combination, mechanism for driving nails into a heel, a shoe support arranged for movement into and out of the range of said mechanism, a movable nail carrier for bringing nails into position to be driven, and power actuated means for reciprocating said carrier arranged to be brought into action by the movement of the shoe support away from said mechanism and at approximately the outward limit of movement of said shoe support.

4. A heel attaching machine, having in combination, mechanism for driving attaching nails into a heel, a shoe support arranged for movement into and out of the range of said mechanism, and power actuated means for supplying nails to said mechanism arranged to be brought into action by the movement of the shoe support away from said mechanism.

5. A heel attaching machine, having in combination, mechanism for driving attaching nails into a heel, a shoe support arranged for movement into and out of the range of said mechanism, and power actuated means constructed for operation independently of said mechanism for supplying nails to said mechanism, said means being arranged to be brought into action by the movement of the shoe support away from said mechanism.

6. In a heel attaching machine, a movable shoe support, a movable heel or top lift holder, and means controlled by movement of the shoe support to an inoperative position for effecting movement of the holder into operative position.

7. In a heel attaching machine, the combination of a shoe support movable to and

from attaching position, and a heel holder movable to and from attaching position, the movement of the holder to attaching position being dependent upon the movement of the shoe support away from attaching position.

8. A heel attaching machine, having in combination, mechanism for driving attaching nails into a heel, a shoe support arranged for movement into and out of the range of said mechanism, and power actuated means for bringing the nails into position to be driven arranged to be brought into action by the movement of the shoe support away from said mechanism.

9. A heel attaching machine, having in combination, mechanism for driving nails into a shoe, a shoe support arranged for movement into and out of the range of said mechanism, a nail carrier for supplying nails to said mechanism and power actuated means for reciprocating the nail carrier between nail receiving and nail delivering positions arranged to be brought into operation by the movement of the shoe support away from attaching position and constructed to move the carrier toward its nail receiving position prior to the movement of the shoe support toward attaching position.

10. A heel attaching machine, having in combination, mechanism for driving nails into a heel, a shoe support arranged for movement into and out of the range of said mechanism, a movable nail carrier for bringing nails into position to be driven and power driven means for reciprocating said carrier arranged to be brought into action at a predetermined point in the outward movement of the shoe support.

11. A heel attaching machine, having in combination, a shoe support, power-actuated mechanism for attaching a heel to a shoe sustained upon said support, power-actuated mechanism for bringing nails into position to be driven and means for controlling the operation of said mechanisms constructed and arranged to permit said mechanisms to be separately and independently brought into operation by the operator.

12. A heel attaching machine, having in combination, mechanism for driving attaching nails into a heel, a shoe support arranged for movement into and out of the range of said mechanism, a movable nail carrier for bringing nails into position to be driven, and automatic means for reciprocating said carrier arranged to be connected with the carrier by the movement of the shoe support away from said mechanism.

13. A heel attaching machine, having in combination, mechanism for driving attaching nails into a heel, a shoe support arranged for movement into and out of the range of said mechanism, a movable nail carrier for bringing nails into position

to be driven, and means for reciprocating said carrier arranged to be connected with the carrier by the movement of the shoe support away from said mechanism and to be automatically disconnected therefrom at the completion of each cycle of operations.

14. A heel attaching machine, having in combination, mechanism for driving attaching nails into a heel, a shoe support arranged for movement into and out of the range of said mechanism, a constantly moving member, a movable nail carrier to be actuated thereby for bringing nails into position to be driven, and means controlled by the outward movement of said shoe support to connect said member and carrier.

15. A heel attaching machine, having in combination, mechanism for driving attaching nails into a heel, a shoe support arranged for movement into and out of the range of said mechanism, a constantly moving driving member, a driven member, a nail carrier connected with the driven member and arranged for movement to position nails in operative relation to said mechanism, and means controlled by the outward movement of said support for connecting said members.

16. In a machine for inserting nails in heels, the combination of a shoe support, a power actuated mechanism for attaching a heel to a shoe sustained upon said support, and a nail carrier arranged to be moved by power toward and away from position to deliver nails to said driving mechanism while said mechanism is idle.

17. In a heel attaching machine, the combination of means for inserting nails into a heel, a shoe support arranged for movement into and out of the range of said means, a movable nail carrier for bringing nails into position to be inserted, power-actuated means for moving said carrier, and means intermediate the shoe support and said power-actuated means permitting limited movement of the shoe support and operative upon further movement of the shoe support to cause the power-actuated means to move the nail carrier.

In testimony whereof I have signed my name to this specification in the presence of two subscribing witnesses.

CHARLES A. POTTER.
